GAME APPARATUS—BULL FIGHT

Manuel Joseph Diaz, Chicago, Ill.

Application July 3, 1934, Serial No. 733,631

3 Claims. (Cl. 272—1)

This invention relates to a novel and improved game apparatus—a bull fight—and consists of the matters hereinafter described and more particularly pointed out in the appended claims.

5 Bull fighting is a national sport in many countries, where it is largely attended and is as popular as baseball, horse racing, and like sports in this country. The sport, however, has little or no appeal to many who might otherwise admire it, 10 because of its reputed gory aspect.

The object of the present invention is to provide a game apparatus by means of which a bull fight with a real bull and horses and the attendant picadors, banderilleros and matadors may be 15 staged or played with all the spectacular action and effect of the real thing—with charging bull, galloping horses and dodging banderilleros, with little or no danger to the actors or players of the game and with absolutely no bloodshed of man, 20 horse or bull.

The advantages of the invention will appear more clearly as I proceed with my specification.

In the drawings:—

Figure 1 is a perspective view showing a bull 25 with a mounted picador with a lance or pike attacking the bull, said lance or pike being connected with an electrical apparatus worn by the picador;

Figure 2 is a perspective view of a belt to be 30 worn by the picador and carrying the electrical apparatus aforesaid;

Figure 3 is a diagrammatical view of the electrical apparatus used in the game;

Figure 4 is a front elevation of one leg of the 35 horse, showing the arrangement for grounding one terminal of the electrical apparatus;

Figure 5 is a sectional view of the shoe worn by the horse and providing a terminal for grounding the current;

40 Figure 6 is a perspective view of a metal band to be engaged about the body of the bull;

Figure 7 is a perspective view of the head of the 45 bull, showing detachable horns connected thereto;

Figure 8 is a perspective view on an enlarged scale, illustrating the lance or pike and its electrical connections; and

Figure 9 is a side elevation partly in section, 50 showing a form of banderilla or dart to be used in the game.

Referring now to the drawings and to that embodiment of the invention illustrated therein:— 55 indicates the bull; 11 indicates a horse; and 12 indicates a horseman to take the part of a picador in the game. The picador carries a rod

13 which is designed to simulate the lance or pike in a real bull fight. 14 indicates a steel or metal band engaged about the body of the bull. Said band is made adjustable so that it may be snugly fixed in place on the bull. As shown, the 5 adjustability is provided by means, as in Figure 6, where the band consists of a strap having its ends turned at right angles to provide flanges 15, 15, which are connected together by a combination spring and turnbuckle construction 16, including thumb nuts 17 for adjusting the tension of the spring.

The rod 13 is made of any suitable material, is tubular and has at its end a metal ferrule 18. An insulated conducting wire 19 extends through 15 the tubular rod 13 and is connected at one end to the ferrule 18. The other end of the conducting wire 19 extends beyond the rod 13, where it has connected to it a socket 20 for engagement with a plug member 21 connected to a conductor 20 wire 19a.

22 indicates a belt of any suitable construction to be worn by the horseman who is to take the part of the picador. Said belt is provided with suitable pockets 23 to receive batteries 24 of the 25 kind use in ordinary flashlights. 25 indicates an induction coil for insertion in the battery circuit and attached to a base 25a which is secured to the belt 22. A switch 26 is interposed in the battery circuit. The conductor 19a is led through 30 or alongside the sleeve of one arm of the picador and then down within his coat or shirt to one side of the induction coil, as shown in Figure 1. 27, 27 indicate terminals to be connected by conductors 27a, 27a to ground. The circuits of these 35 conductors are grounded through the hoofs of the horse and, since the horse when in action will have only one of either front or rear pairs of hoofs on the ground, one conductor is associated with each of two pairs of hoofs, as for example, 40 the two front hoofs.

As terminals for the ground wires, steel soled rubber boots or shoes 28 are provided for each of the two front hoofs of the horse. 29 indicates the outer steel sole of the boot. A ground wire 45 27a is led down inside the upper of the boot 28 and down through the inner sole 28a of said boot, where it is bent along and into contact with the top face of the metal sole 29 to which it is electrically connected, as indicated at 29a. The steel 50 sole 29 is connected in any convenient manner to the inner sole 28a, as by rivets 28b.

The electrical connections are indicated diagrammatically in Figure 3, with like letters of reference.

In order that there may be no danger of goring by the horns of the bull, the bull used in the game is dehorned and his horns are replaced by rubber or leather forms 30, 30, made to simulate 5 horns slit at their base to be adjustable in diameter, with lacings or other means 31 for securing them to the stubs left after dehorning the bull. When the bull, provided with such horns, attacks a horse or man, the horns will yield and 10 the danger of injury from the charging bull is reduced to a minimum and goring absolutely prevented.

To still further simulate the actual bull fight, darts or banderillas 32 are provided. These consist of short shafts, as indicated in Figure 9, feathered at one end as shown at 33 and having 15 vacuum cups 34 fixed to the other end in any convenient manner. When thrust or discharged at the bull, the cup will act to affix the dart to 20 the hide of the bull, from which it will project in simulation of the actual dart or banderilla used in a regular bull fight.

In playing the game, after the release of the 25 bull into the ring, the horseman or picador, having equipped himself with the belt 22 and with the lance or pike 13 properly connected to the electrical circuit as hereinbefore described, mounts the horse 11 equipped with the steel soled, insulated boots 23 and connects the conductor wires 27a to the terminals 27, as hereinbefore described. The picador then rides at the 30 bull (which has been preferably equipped before being led into the ring with the band 14) and engages the ferrule 18 of the lance or pike 13 against said metal band 14. Induced current of 35 high voltage is immediately grounded through the band 14 and the hoofs of the bull, with a resulting distinct shock to the bull. As the current is low, however, the shock is without injury 40 to the bull. This enrages the bull and arouses him to greater activity in the game. This may be repeated by one or more picadors in simulation of a regular bull fight, while in the meantime the banderilleros add to the spectacle of 45 the game by throwing the darts which engage and stick to the hide of the bull.

Suitable stockings or wrappings 35, 35 are provided for extending the conductors 27a, 27a down alongside the legs of the horse, as shown in 50 Figures 1 and 4, to properly hold them without interfering with the action of the legs of the horse. Said conductors in their path from the upper leg of the horse to the belt will be concealed by the legs of the rider wearing the usual 55 chaps, as pictured in Figure 1. The rider will also be equipped with a suitable gauntlet 36, within which will be concealed the plug and 60 socket 21, 20 by which connection may be made or broken between the conductor on his body and the conductor in the lance or pike.

The advantages of and the manner in which the game may be extended to simulate the regu-

lar bull fight, will be obvious to those familiar with that art.

The band 14 to be worn by the bull, may be omitted. With the voltage developed in the induction coil, the current through the conducting wire 19 may be grounded through the body of the bull when the ferrule or contact 18, in which said conductor ends, touches the bull at any point. 5

I claim as my invention:—

1. A game apparatus for simulating bull fighting, comprising a ferrule shod lance, an insulated conductor connected to said ferrule and extending therefrom along said lance and beyond the grip end of said lance, a plurality of low current 15 low voltage batteries, an induction coil suitably mounted in association with said batteries, an auxiliary conductor adapted to connect the secondary of said induction coil to the conductor projecting beyond the grip end of said lance, 20 ground conductors for the secondary of said induction coil adapted to be grounded through the hoofs of a horse upon which the rider is mounted, and insulation metal shod boots for attachment to the horse's hoofs, said ground conductors being 25 severally connected to the metal of said metal shod boots.

2. A game apparatus for simulating bull fighting, comprising a ferrule shod lance, an insulated conductor connected to said ferrule and 30 extending therefrom along said lance and beyond the grip end thereof, a belt to be worn by a rider, a plurality of low current low voltage batteries, an induction coil suitably mounted and connected to said belt in association with said batteries, an auxiliary conductor adapted to connect the secondary of said induction coil to the conductor projecting beyond the grip end of said lance, and ground conductors for the secondary of said induction coil adapted to be grounded 35 through the hoofs of a horse upon which the rider is mounted. 40

3. A game apparatus for simulating bull fighting, comprising a ferrule shod lance, an insulated conductor connected to said ferrule and extending 45 therefrom along said lance and beyond the grip end thereof, a belt to be worn by a rider, a plurality of low current low voltage batteries, an induction coil, means for securing said batteries and said induction coil to said belt, an auxiliary 50 conductor adapted to connect the secondary of said induction coil to the conductor projecting beyond the grip end of said lance, ground conductors for the secondary of said induction coil adapted to be grounded through the hoofs of a 55 horse upon which the rider is mounted, and insulation metal shod boots for attachment to the horse's hoofs, said ground conductors being severally connected to the metal of said metal shod boots. 60

MANUEL JOSEPH DIAZ.
